BROODER

Arthur A. Welborn, Rogers, Ark.

Application September 26, 1944, Serial No. 555,833

12 Claims. (CL 119—31)

The present invention relates to brooders and, more particularly, to simple, efficient and economical means for housing chicks, ducklings and other young fowl or birds.

An important feature of the invention consists in providing a vented double cover or hood having a lower or inner cover and a spaced outer cover constituting the cover of the brooder. Suitable heating means are associated with the brooder in such a manner as to insure the heat circulating uniformly under the brooder without creating an undesirable draft. The lower cover which, preferably, is of conical shape is closed at the top and opened at the bottom while the outer cover is of similar shape and is opened both at the top and the bottom, and the heating units are so disposed relative to the covers as to cause the heated air circulating through the brooder to pick up or absorb any moisture that may collect within the brooder. Additionally, the space between the covers of the brooder constitutes means for removing foul air from the floor or the ground and discharges the same through a centrally disposed draft flue vent, thus insuring a constant flow of fresh heated air under the brooder from the bottom or open end thereof.

Other objects and advantages of the invention will become apparent from the following description when taken in conjunction with the accompanying claims and drawings.

Referring to the drawings in which are shown several preferred embodiments of the invention,

Figure 1 is a vertical, sectional view of the brooder constructed in accordance with the present invention;

Figure 2 is a sectional plan view taken substantially along the line 2—2 of Figure 1;

Figure 3 is a bottom view of Figure 1;

Figure 4 is a detailed plan view of one of the combustion chambers;

Figure 5 is a side elevation of Figure 4;

Figure 6 is an end view of Figure 4;

Figure 7 is a detailed longitudinal, sectional view of the upper end of the combustion chamber;

Figure 8 is a sectional view taken substantially along the line 8—8 of Figure 4;

Figure 9 is a detailed plan view of one of the supporting legs;

Figure 10 is an enlarged sectional view taken substantially along the line 10—10 of Figure 1;

Figure 11 is a detailed side view with parts in section showing a modified form of leg structure connected to the brooder;

Figure 12 is an enlarged detailed side view of the leg structure shown in Figure 11;

Figure 13 is a view taken substantially along the line 13—13 of Figure 12, and

Figure 14 is a section taken substantially along the line 14—14 of Figure 12.

Referring to the drawings, the brooder comprises a supporting frame preferably formed of four uniformly spaced L-shaped inclined bars 10 which diverge downwardly from the center of the brooder. A lower or inner cover 11 of substantially conical shape is attached to the horizontal arms 12 of the bars by any suitable means such as the threaded bolts 14 and nuts 13 (Figure 10), and has its upper end 15 closed. Leg members 16 are connected to the lower end of the bars 10 as at 17 (Figure 9) so as to space the open bottom of the cover 11 away from the floor or ground. The feet or leg members 16 are preferably of V-shape having a wide ground-contacting base 18 so as to constitute a firm support for the brooder.

An outer conical shaped cover 19 surrounds the inner cover 11 and is spaced therefrom by the brace members 20 positioned adjacent the upper and lower ends of the covers. Preferably, the brace members are formed with flanges 21 and 22 (Figure 10) and the flanges 21 are secured to the outer cover 19 by the threaded bolts

23 and nuts 24 while the flanges 22 are arranged to rest against the lower cover 11 so that the outer cover 19 may, if desired, be removed from the brooder. The top or upper end of the outer cover 19 is provided with an annular opening 25.

The lower ends of the covers may be beaded as at 26 to receive an annular rod 27 so as to reinforce and strengthen the same. Each of the covers 11 and 19 may be constructed of any suitable metal and formed either in one piece or separate connected sections, and while preferably of conical shape may assume other desired configurations.

Preferably, four uniformly spaced heating units 28 are associated with the brooder and as each of these units is substantially the same in construction and operation, only one will be specifically described. Each heating unit may comprise a substantially rectangular housing or casing 28 (Figure 4) connected to the underside 50 of the lower cover 11 adjacent the bars 10 by bolts or other suitable fastening means 29. The interior of each housing 28 is divided centrally by a partition plate 30 into two separate combustion chambers 31 and 32 which communicate with each other through an opening 33 adjacent the

upper end of the partition 30 so as to insure the heated gases circulating through the housing and distributing the heat uniformly under the brooder. A main gas supply line 34 (Figure 3) communicates with four branch supply pipes 35 by a coupling 36 connected to one of the supply pipes. Each of the pipes 35 connects at its upper end to a central fitting 37 and is arranged to fit longitudinally within the space between the arms of the L-shaped bars 10 (Figure 10) and is suitably bent or provided with elbows 38 and 39 (Figure 4) so as to extend through an opening 40 in one end of the housing 28 and be connected to a slotted cap jet gas burner 41 in the chamber 31. The opening 40 in the housing 28 is provided with a rotatable perforated cap 42 for adjustably controlling the supply of air into the chamber 31 so as to provide a proper combustible mixture. The products of combustion or heated gas from the chamber 31 are conducted into the chamber 32 through the opening 33 in the partition 30. Vent pipes 43 positioned between the covers 11 and 19 communicate through elbows 44 at the lower ends thereof with flanged openings 45 in the chambers 32 so as to withdraw the heated gases therefrom. Each elbow 44 is securely fastened to the flanged opening 45 as at 46 to prevent the escape of heated gases at the point of connection. The upper discharge ends of the vent pipes 43 extend through the opening 25 in the outer cover and into a removable tubular draft cap diverter 47 which is suitably mounted on the brooder immediately above the opening 25. The diverter 47 is preferably of frusto-conical shape and is provided above the outlet of the vent pipes 43 with spaced baffles 48, preferably of progressively decreasing diameters, and communicates at its upper reduced end with a vent discharge flue 49. The vent or gas discharge pipes 43 provide heat radiating surfaces which coact with the walls of the housings 28 and the inner cover 11 to provide a substantial heat radiating area that thoroughly and uniformly heats the space beneath the hover of the brooder. The opening 25 in the top of the cover 19 allows heated air circulating through the space between the covers to be discharged into the room in which the brooder is located to heat the same.

Each housing 28 has a flat top 50 (Figure 10) that contacts at its corners with the curved portion of the inner cover 11 thus providing a space or clearance 51 between the housing and the cover 11 to permit the slow circulation of the heated air under the brooder without creating any undesirable draft which quite frequently causes the loss of chicks or other poultry or young birds protected by the brooder. Preferably, the bottom 52 of the housing 28 is formed at its opposite edges with inwardly extending flanges 53 that cooperate with complementary flanges 54 on the housing 28 to provide a removable or slidible lid to permit ready access to the chambers 31 and 32 to clean the same or to adjust the burners. The gas supply line 34 is preferably provided with a thermostat 55 (Figure 1) for automatically controlling the temperature under the brooder within the desired range and a valve 56 for regulating the flow of the gas or other heating medium to the burners.

The upper cover 19 is removable so that in warm weather and when it is not necessary to heat the room, the cover 19 may be detached from the brooder. At the same time the flow of the fuel to the burners may be controlled to provide the desired amount of gas or fuel to prop-

erly heat the brooder, so as to economize on fuel consumption. The brooder is of such size and is spaced from the ground the desired distance to accommodate the chicks, and the heating units 27 are disposed adjacent the outer perimeter of the inner cover 11 to insure the chicks being kept warm without danger of being subjected to an undesirable draft.

In operation, the thermostat 55 is set at the desired temperature and the valve 56 turned on and the four burners are lit so that the heat generated will completely warm the entire brooder house and, at the same time, maintain the desired temperature required under the brooder at a very low cost of fuel consumption. As the heated gases discharge upwardly through the vent pipes 43 into the diverter 47, they are broken up by the baffles 48 so as to slow up their speed of discharge prior to being delivered to the vent pipe 49. The parts are constructed and arranged so as to be readily dismantled for the purpose of inspection and repair and, when once in operation, the temperature of the brooder is maintained automatically at the desired range, and the heated air circulates under the brooder without creating an undesirable draft.

In the modified form of the invention shown in Figure 11, the brooder is substantially the same in construction and operation as the form previously described. Instead of the fixed legs 16, adjustable supporting members or feet are provided which comprise a pair of spaced depending arms 57 pivoted as at 58 to the lower end of each of the bars 10. A brace 59 is also pivotally connected as at 60 to the arm 10. A substantially triangular shaped foot 61 (Figure 13) has parallel spaced upwardly extending arms 62 between which extend the arms 57. The arms 57 and 62 are provided with a series of vertically disposed spaced openings 63 and the brace 59 with two spaced openings 64. A pair of threaded bolts 65 are arranged to extend through the aligned openings 63 in the bars 57 and arms 62 and the openings 64, so that upon the application of the nuts 66 to maintain the parts in a fixed position. Thus, it will be seen that each foot 61 may be adjusted vertically relative to the brooder so as to properly space the same away from the floor or ground by removing the bolts 65 and nut 66 and adjusting the foot 61 to the desired length and then inserting the bolts through the pair of openings in the brace 59 and the aligned openings 63 in the bars 57 and the sides 62 so that upon tightening up the nuts 66, the parts are secured firmly in position. The brace 59 is arranged to be positioned between the arms 57 and when connected to the foot 61 and the arms 57 through the bolts 65, insure the feet being maintained in their adjusted position.

Thus, it will be seen that the vented double cover of the brooder provides means for uniformly distributing the heat over the entire area covered by the brooder without the creation of draft. Moreover, the circulation of the heated air between the housings 28 and the lower cover 11 through the passages 51 coacts with the heat radiated from the vent pipes 28 to pick up or absorb any moisture that might accumulate under the brooder. The space between the covers also serves to remove foul or contaminated air from the floor or ground and discharges the same upwardly through the diverter 47 to the vent pipe 49, thus insuring the circulation of clean air at the proper temperature under the brooder and 75 into the room.

It will be understood that the forms of the invention shown and described are merely illustrative or preferred embodiments and that such changes may be made as fall within the purview of one skilled in the art without departing from the spirit of the invention and the scope of the claims.

I claim:

1. A brooder comprising a frame, a substantially conical shaped cover supported by said frame, heating chambers beneath said cover adjacent the lower edge thereof, and heating pipes leading from said chambers through the above said cover to the top thereof. 10
2. A brooder comprising a frame, a cover supported by said frame, heating chambers beneath said cover adjacent the lower edge thereof, heating pipes leading from said chambers through and above said cover to its top, and a second cover spaced from said first-named cover and having an open top to which said pipes deliver. 15
3. A brooder comprising a frame, a substantially conical shaped cover supported by said frame and closed at its top, combustion chambers beneath said cover adjacent the lower edge thereof, burners in said chambers, pipes leading from said chambers through and above said cover to its top, and a second cover spaced from and enclosing said first-named cover and pipes and having an open top into which said pipes deliver. 20
4. A brooder comprising a frame, a substantially conical shaped cover supported by said frame and closed at its top, combustion chambers beneath said cover adjacent the lower edge thereof, burners in said chambers, pipes leading from said chambers through and above said cover to its top, a second cover spaced from and enclosing said first-named cover and pipes and having an open top into which said pipes deliver, and means for removably mounting the second cover on the brooder. 25
5. A brooder comprising a frame having spaced downwardly and outwardly inclined bars, a cover connected to said bars, heating chambers beneath said cover adjacent its lower edge, heating pipes leading from said chamber through and above said cover to the top of the bars, adjustable legs connected to the lower ends of said bars for supporting the brooder above the ground, each leg including an upper portion and a lower ground engaging portion, the lower portion being movable longitudinally relative to the upper portion, braces pivoted at their upper ends to said bars, and means for adjustably securing the leg portions and the braces in a fixed position. 30
6. A brooder comprising a frame, a substantially cone shaped lower cover supported by said frame and closed at its top, combustion chambers beneath said cover and spaced circumferentially around the lower edge thereof, burners in said chambers, an outer conical shaped cover spaced from said lower cover, and pipes leading from said combustion chambers through said lower cover and extending upwardly between said covers for discharging the products of combustion from the brooder. 35
7. A brooder comprising a frame, a substantially cone shaped lower cover supported by said frame and closed at its top, combustion chambers beneath said cover and spaced circumferentially around the lower edge thereof, burners in said chambers, an outer conical shaped cover spaced from said lower cover and having an opened top, and pipes leading from said combustion chambers through said lower cover and extending upwardly between said covers for discharging the products of combustion from the brooder. 40
8. A brooder comprising a frame having spaced downwardly and outwardly inclined bars provided with legs at their lower ends, a substantially conical shaped inner cover supported by said bars and having a closed top, an outer cone shaped cover spaced from said inner cover and having an open top, a tubular draft cap diverter mounted on the brooder above said open top, combustion chambers connected to the underside of the inner cover adjacent the lower edge thereof, the intermediate portions of said combustion chambers being spaced from the inner cover to provide air circulating passages, burners in said chambers, pipes leading from said chambers through and above said inner cover and extending upwardly between said covers into said diverter for withdrawing the products of combustion from the brooder. 45
9. A brooder comprising a frame having spaced downwardly and outwardly inclined L-shaped bars, legs connected to the lower ends of said bars, a substantially conical shaped inner cover supported by said bars and having a closed top, an outer cone shaped cover spaced from said inner cover and having an open top, housings connected to the underside of the inner cover adjacent the lower edge thereof, each of said housings having a partition therein dividing the same into separate combustion chambers, a burner in one of said chambers, said partition having an opening adjacent one end communicating said chambers with each other, a fuel supply line having branch pipes disposed adjacent said bars, each of said branch pipes being connected with a burner, and the other chamber in each of said housings having a pipe communicating therewith and extending through the lower cover and upwardly between said covers for discharging the products of combustion from the brooder. 50
10. A brooder comprising a frame having spaced downwardly and outwardly inclined L-shaped bars, legs connected to the lower ends of said bars, a substantially conical shaped inner cover supported by said bars and having a closed top, an outer cone shaped cover spaced from said inner cover and having an open top, housings connected to the underside of the inner cover adjacent the lower edge thereof, each of said housings having a partition therein dividing the same into separate combustion chambers, a burner in one of said chambers, said partition having an opening adjacent one end for communicating said chambers with each other, a fuel supply line having branch pipes disposed adjacent said bars, each of said branch pipes being connected with a burner, the other chamber in each of said housings having a pipe communicating therewith and extending through the lower cover and upwardly between said covers for discharging the products of combustion from the brooder, and the intermediate portions of said housings being spaced from the inner cover to provide air circulating passages within the brooder. 55
11. A brooder comprising a frame having spaced downwardly and outwardly inclined bars, vertically adjustable legs connected to the lower ends of said bars, means for maintaining the legs in a fixed adjusted position, a substantially conical shaped inner cover supported by said bars and having a closed top, an outer cone shaped cover spaced from said inner cover and having an open top, and pipes leading from said combustion chambers through said lower cover and extending upwardly between said covers for discharging the products of combustion from the brooder. 60

top, combustion chambers connected to the underside of the inner cover adjacent the lower edges thereof, pipes leading from said chambers through and above said inner cover and extending upwardly between said covers into the open top of the outer cover, and a vent flue communicating with the upper ends of said pipes for withdrawing the products of combustion from the brooder.

12. A brooder comprising a frame having a spaced downwardly and outwardly inclined bars, vertically adjustable legs connected to the lower ends of said bars, means for maintaining the legs in a fixed adjusted position, a substantially conical shaped inner cover supported by said bars and having a closed top, an outer cone shaped 15

5 cover spaced from said inner cover and having an open top, combustion chambers connected to the underside of the inner cover adjacent the lower edge thereof, pipes leading from said chambers through and above said inner cover and extending upwardly between said covers into the open top of the outer cover, a vent flue communicating with the upper ends of said pipes for withdrawing the products of combustion from the brooder, and the intermediate portions of said combustion chambers being spaced from the inner cover to provide air circulating passages within the brooder.

ARTHUR A. WELBORN.
